UNITED STATES PATENT OFFICE.

THOMAS DOWSLEY KENNEDY, OF OWEN SOUND, ONTARIO, CANADA.

STAKE POCKET FOR VEHICLES.

Application filed March 3, 1926. Serial No. 92,001.

This invention relates to the pockets employed at the sides of vehicles to receive the lower ends of load retaining stakes, and my object is to devise a form of pocket which 5 releasably retains the stake in position and which is adapted for remote control.

I attain my object by providing each pocket with a gate or gates and with releasable means, adapted for remote control, for 10 locking the gates in their closed position, means are also provided for forcibly ejecting the stake after the gates have been opened. The whole is constructed in detail as hereinafter more specifically described 15 and as illustrated in the accompanying drawings in which

Fig. 1 is a plan view of a stake pocket constructed in accordance with my invention;

Fig. 2 a front elevation of the same;

Fig. 3 a plan view of the underside of the same;

Fig. 4 a side elevation, partly in section;

Fig. 5 a side elevation, on an enlarged 25 scale, showing one form of the locking device;

Fig. 6 a similar view showing a modification of the locking device; and

Fig. 7 a plan view of part of Fig. 6.

In the drawings like numerals of reference indicate corresponding parts in the different figures.

1 is a back plate, on which are formed lugs 2 forming two spaced sets of hinge 35 knuckles. Gates 3 are formed with hinge knuckles co-operating with the lugs 2 aforesaid and pivotally connected therewith by means of the hinge pins 5. The space between the lugs is sufficient to receive the 40 lower end of a stake 6, the back plate forming the back of the pocket, the lugs 2 the sides, and the gates 3 the front of the pocket. Each gate is provided with a tail 7 extending away from the pocket. At its lower 45 end each gate is provided with a lug 8 adapted to engage a shoulder 9 formed on the adjacent lug 2. These lugs and shoulders thus form stops limiting the closing movement of the gates. On each hinge pin 50 5 is positioned a coil spring 10, one end of each spring being connected with one of the lugs 2 and the other with the gate. These springs tend to close the gates. The gates are adapted to be locked in their closed 55 position by means of latches 11 adapted to

move to and from a position between the tails and the back plate 1.

In Figs. 1 to 5 of the drawings I show the latches 11 as rectilinearly slidable in the guides 12. The latches are operated by 60 means of cranks 13 clamped on a square shaft 14, the cranks being connected by means of pivoted connecting rods 15 with their respective latches.

In Figs. 6 and 7 a slight modification is 65 illustrated, each latch 11^a being provided with round projections 16 adapted to slide in the grooved guides 17 formed on the back plate. The crank 13 is pivoted directly to the lower end of the latch, so that the latter 70 must necessarily rock on its projections 16 as it is moved to and from its operative position. A rearwardly extending projection 18 is provided on each latch adapted to engage the back plate to limit its movement 75 when it is thrown up to its operative position engaging behind the tail 7.

To support the lower end of the stake and to provide means for positively ejecting the lower end of a stake when the gates are released, I provide a rotatable supporting and ejecting member 19. This is formed of a clamp 20 adapted to be clamped about the square shaft 14. The member 19 is formed with an arc-shaped supporting surface 21 so that, as the shaft is rotated to release the latches, no upward movement is imparted to the stake. A shoulder 22 is formed on the member 19 which, when the latches are 80 fully released, comes to a position to engage 90 the lower back corner of the stake and thus, as the shaft is further rotated, forces the stake outward, in case for any reason it has become stuck or jammed so that the pressure of the load does not eject it. The clamp 95 20 has a cylindrical projection 23 which has a bearing in the lug 24 formed on the back plate 1. As every stake pocket along the 100 length of the vehicle is similarly constructed, suitable bearings are thus provided for the shaft 14. At one or both ends the shaft will be provided with operating means, such as now known in the art, and which requires no specific description.

What I claim is:

1. A stake pocket having a back plate and an open front; a pair of hinged gates forming the front of the pocket and adapted when closed to retain a stake in the pocket; springs tending to close the gates; a tail on 110

each gate extending laterally from the pocket; and releasable locks carried by the back plate adapted to engage the tails remote from the pocket to retain the gates in 5 their pocket closing position.

2. A stake pocket having an open front; a hinged gate adapted when closed to retain a stake in the pocket; a tail on said gate; a guide for a latch; and a latch slid able in the 10 guide to and from a tail engaging position.

3. A stake pocket comprising a back plate; a stake supporting member; lugs spaced to receive a stake between them and forming hinge knuckles; a pair of gates 15 forming the front of the pocket and provided with hinge knuckles co-operating with the lugs aforesaid; hinge pins pivotally connecting the knuckles; tails on the gates; and releasable latches adapted to lock the tails 20 with the gates in closed position.

4. A stake pocket comprising a back plate; a stake supporting member; lugs spaced to receive a stake between them and forming hinge knuckles; a pair of gates 25 forming the front of the pocket and provided with hinge knuckles co-operating with the lugs aforesaid; hinge pins pivotally connecting the knuckles; tails on the gates; releasable latches adapted to lock the tails 30 with the gates in closed position; and stops limiting the closing movements of the gates.

5. A stake pocket comprising a back plate; a stake supporting member; lugs spaced to receive a stake between them and forming hinge knuckles; a pair of gates 35 forming the front of the pocket and provided with hinge knuckles co-operating with the lugs aforesaid; hinge pins pivotally connecting the knuckles; tails on the gates; releasable latches adapted to lock the tails 40 with the gates in closed position; stops limiting the closing movements of the gates; and springs tending to close the gates.

6. A stake pocket having an open front; 45 a hinged gate adapted when closed to retain a stake in the pocket; a releasable lock adapted to retain the gate in its pocket closing position; lock releasing means; and means for ejecting a stake after the gate is 50 released operable by the lock releasing means.

7. A stake pocket having an open front;

a hinged gate adapted when closed to retain a stake in the pocket; a releasable lock adapted to retain the gate in its pocket closing position; rotatable means adapted to support the lower end of a stake; and a projection on said means adapted when the said means is rotated to engage and eject the stake. 55

8. A stake pocket comprising a back plate; a stake supporting member; lugs spaced to receive a stake between them and forming hinge knuckles; a pair of gates 60 forming the front of the pocket and provided with hinge knuckles co-operating with the lugs aforesaid; hinge pins pivotally connecting the knuckles; tails on the gates; releasable latches adapted to lock the tails 65 with the gates in closed position; a shaft journaled on the bottom part of the plate; means operable by the shaft for moving the latches; and a stake ejector secured to the shaft adapted when the shaft is rotated to engage and eject the stake. 70

9. A stake pocket comprising a back plate; a stake supporting member; lugs spaced to receive a stake between them and forming hinge knuckles; a pair of gates 75 forming the front of the pocket and provided with hinge knuckles co-operating with the lugs aforesaid; hinge pins pivotally connecting the knuckles; tails on the gates; releasable latches adapted to lock the tails 80 with the gates in closed position; a shaft journaled on the bottom part of the plate; means operable by the shaft for moving the latches; and a stake support and ejector secured to the shaft normally supporting the stake but adapted to engage and eject it 85 when the shaft is suitably rotated. 90

10. A stake pocket having a back plate and an open front; a pair of hinged gates forming the front of the pocket and adapted when closed to retain a stake in the pocket; 95 a tail on each gate extending laterally from the pocket and releasable locks carried by the back plate adapted to engage the tails remote from the pocket to retain the gates in their pocket closing position. 100

Signed at Owen Sound this 4th day of February, 1926.

THOMAS DOWSLEY KENNEDY.
